FLUID JOINT

Asa J. Taylor, Zion, Ill., assignor, by mesne assignments, to Trifam Manufacturing Company, Maywood, Ill., a corporation of Illinois

Application January 24, 1944, Serial No. 519,478

5 Claims. (Cl. 285—96.3)

1

My invention relates to structure comprising members hingedly connected together to permit of relative movement of said members and wherein it is desired that provision be made for the passage of fluid through the hinge-joint and in at least one of said members.

My primary object is to provide such a structure whereby the fluid in its travel through one or both of the hingedly connected members in the different relative positionings of said members travels through the pin of the hinge, and the joint formed between the pin and the structure comprising said members is rendered fluid tight; other more specific objects will be understood from the following description.

Referring to the accompanying drawings:

Figure 1 is a broken view in vertical sectional elevation of a hydraulic jack construction, embodying the invention and involving the flowing of the fluid from a source thereof to the ram of the jack and its return to said source through the same course;

Figure 2 is a section taken at the line 2—2 on Fig. 1 and viewed in the direction of the arrows;

Figure 3 is a broken view in sectional elevation of another construction embodying the invention in which the fluid is caused to travel from a source thereof through one course for its intended purpose and thereafter to travel through another course;

Figure 4 is a section taken at the line 4—4 on Fig. 3 and viewed in the direction of the arrow;

Figure 5 is a view like Fig. 1 of another embodiment of the invention in a hydraulic jack wherein the flow of the fluid to the ram and its return to the source is through the same course; and

Figure 6, a section taken at the line 6 on Fig. 5 and viewed in the direction of the arrow.

Referring to the construction shown in Figs. 1 and 2 it involves two members 7 and 8 which it is desired be hingedly connected together, the member 7 having a passage 9 therein which would communicate with a pump connected with a receptacle (not shown) carried by the member 7 and in which the hydraulic fluid to be used would be contained. The member 8, shown as in the form of a head, providing a cylinder 10 in which the ram 11 of the jack is slidable, has a passage 12 opening at one end into the bottom of the cylinder 10.

The member 7 is formed at one end with a fork-portion affording spaced apart legs 13 and 14 in the space between which an ear 15 on the head 8 is located.

2

The legs 13 and 14 and ear 15 are bored cross-wise thereof, as represented at 16, 17 and 18, respectively, to provide a tapered opening 19 extending through these legs and ear and forming a bearing for a tapered hinge pin 20, the passages 9 and 12 opening through the leg 14 and the ear 15, respectively, into the interior of the bearing.

The tapered hinge pin 20 has two spaced apart arcuate grooves 21 and 22, shown as endless, in its periphery, with a cross-groove 23 communicating at its ends with the grooves 21 and 22, respectively, these grooves forming passages for fluid. The pin 20 is located in the tapered bearing-opening 19, with its grooves 21 and 22 registering with the passages 9 and 12, respectively, regardless of the positionings of the members 7 and 8 relative to each other about the axis of the hinge pin, and is drawn into such tight engagement with the wall of the opening 19 by a self-locking nut 23 screwed on the small end of the pin 20 against a washer 24 which bears against the outer surface of the leg 13, as to render the joint between the pin 20 and the bearing sufficiently tight to prevent leakage of fluid, especially when under relatively high pressure, out of the bearing-opening 19, but still permit of the relative movement of the members 7 and 8 about the axis of the hinge pin 20.

As will be understood, in the use of the jack, fluid is forced, as for example by the pump referred to, to the ram-cylinder 10 for actuating the ram, through the passage 9 to the hinge pin 20, the fluid entering the groove 21 and thence passing through the cross-groove 23 to the groove 22 from which it passes into passage 12 and thence to the cylinder.

This particular construction as above stated contemplates the return of the actuating fluid to the source from which it was supplied, through the same course, but in a reverse direction, as that traveled by the fluid in passing to the cylinder.

Referring to the construction shown in Figs. 3 and 4 wherein it is contemplated that the fluid to be conducted to the point of use will flow through one course from a supply thereof and flow from the point of use through another course, the construction shown involves two members 24 and 25 which it is desired be hingedly connected together. The member 24 has passages 26 and 27, respectively, therein, the passage 26 leading from a source of supply (not shown) of the fluid to be used and the other passage 27 leading to any desired point of discharge of the fluid. The

member 25 has passages 28 and 29, the passage 28 leading to the point of use of the fluid, and the passage 29 leading away from such point of use.

The member 24 has a forked end presenting spaced-apart legs 30 and 31, and the member 25 has an ear 32 which extends into the space between the legs. The legs 30 and 31 and the ear 32 are bored crosswise thereof as represented at 33, 34 and 35, respectively, to provide a tapered opening 36 extending through these legs and the ear and forming a bearing for a tapered hinge pin 37, the passages 26 and 27 opening through the legs into the interior of the bearing and the passages 28 and 29 opening through the ear 32 into the interior of the bearing.

The tapered hinge pin 37 has four spaced-apart arcuate grooves 38, 39, 40 and 41, shown as endless, in its periphery, with a cross-groove 42 communicating at its ends with the grooves 38 and 39, and a cross-groove 43 communicating at its ends with the grooves 40 and 41, all of these grooves forming passages for fluid.

The pin 37 is located in the tapered bearing-opening 36, with its grooves 38, 39, 40 and 41 registering, with the passages 27, 29, 28 and 26, respectively, regardless of the positionings of the members 24 and 25 relative to each other about the axis of the hinge pin, and is drawn into tight engagement with the wall of the opening 36 as in the case of the construction shown in Figs. 1 and 2 and for the same purpose, the nut and washer of this construction being represented at 44 and 45, respectively.

As will be understood from the foregoing, fluid supplied to the passage 26 passes into the groove 41 thence to groove 40 through the cross-groove 43 and from groove 40 to the passage 28 in member 25 from which it passes to the point of use; the fluid in leaving the point of use would pass into the passage 29 in member 25, thence into the groove 39 and through the cross-groove 42 to groove 38 and then into passage 27 in the member 24 through which it would flow to the desired point of disposal.

Referring to the construction shown in Figs. 5 and 6 which is in the form of a hydraulic jack as in the case of the construction shown in Figs. 1 and 2, the two members corresponding with the members 7 and 8 being indicated at 46 and 47, the member 46 has a forked end affording spaced-apart lugs 48 and 49 into the space between which an ear 50 on the member 47 is located, the lugs and ear being bored transversely to provide a tapered bearing-opening 51 for a tapered hinge pin 52. The hinge pin 52 is provided with a passage 53 extending lengthwise of the pin for connection at a boss 54 on the pin with a hose 55 provided for the same purpose as the passage 9 in the member 7, the upper end of the hose 55 being connected with the member 46 and opening into a passage (not shown) communicating with the pump of the jack. The passage 53 opens into a cross-passage 56 in the pin which, in turn, opens into an arcuate groove 57, shown as endless, in its periphery, which registers with one end of a passage 58 in the member 47 regardless of the positionings of the members 46 and 47 relative to each other about the axis of the hinge pin, the opposite end of the passage 58 opening into the ram cylinder indicated at 59.

The pin 52 is provided with a nut 60 and washer 61 as, and for the purpose, explained of the nut 75

and washer in the construction shown in Figs. 1 and 2.

Preferably the hinge pin in each of the constructions shown conformingly fits the wall of the bearing-opening throughout the length of the portion of the pin within the bearing opening.

While I have illustrated and described certain particular constructions embodying my invention, I do not wish to be understood as intending to limit the invention thereto as the same may be variously modified and altered and the invention embodied in other forms of structure, without departing from the spirit of the invention.

15 What I claim as new and desire to secure by Letters Patent is:

1. A structure comprising a plurality of members having lapping portions, and fluid-joint means for hinging said members together comprising a hinge pin located in certain of said lapping portions and in fluid-joint-forming relation to certain of said members; said members having fluid passages opening to said pin and said pin having fluid passages through which fluid may flow from one to the other of said members in the various positions of said members relative to each other angularly about the longitudinal axis of said pin.

2. A structure comprising a plurality of members 30 having parallel lapping portions, and fluid-joint means for hinging said members together comprising a hinge pin located in certain of said lapping portions and in fluid-joint-forming relation to certain of said members, each of said members having a fluid passage opening to said pin, said pin having arcuate grooves in its periphery in communication with each other and registering with the passages in said members, respectively.

3. A structure comprising a plurality of members having parallel lapping portions, and fluid-joint means for hinging said members together comprising a tapered hinge pin located in certain of said lapping portions and in fluid-joint-forming relation to certain of said members, each of said members having a fluid passage opening to said pin, said pin having arcuate grooves in its periphery in communication with each other and registering with the passages in said members, respectively, the communication between said arcuate grooves including a groove in the pin connecting said arcuate grooves.

4. A structure comprising a plurality of members having lapping portions, and fluid-joint means for hinging said members together comprising a hinge pin located in said lapping portions and in fluid-joint-forming relation thereto, each of said members having a pair of fluid passages opening to said pin, said pin having two sets of arcuate grooves in its periphery, one of the grooves of each set being in communication with the other groove of the set, one groove of each set registering with the passages, respectively, in one of said members and the other groove of each set registering with the passages, respectively, in the other of said members.

5. A structure comprising a plurality of members having lapping portions, and fluid-joint means for hinging said members together comprising a tapered hinge pin located in said lapping portions and in fluid-joint-forming relation thereto, each of said members having a pair of fluid passages opening to said pin, said pin having two sets of arcuate grooves in its periphery, one of the grooves of each set being in communication with the other groove of the set, one groove of each set registering with the passages, respectively, in one of the members and the other groove of each set registering with the passages, respectively, in the other of the members.

cation with the other groove of the set by means of a groove in the pin connecting them together, one groove of each set registering with the passages, respectively, in one of said members and the other groove of each set registering with the 5 passages, respectively, in the other of said members.
